UNITED STATES PATENT OFFICE

FRANK J. FAASE, OF MILWAUKEE, WISCONSIN

CUTTING DEVICE

Application filed September 27, 1929. Serial No. 395,536.

My invention relates to improvements in cutting devices.

The object of my invention is to provide a device for accurately cutting grooves, channels or strips in and from the surfaces of floors or materials where moldings or inserts are desired to be inlaid.

More specifically stated it is an object of my invention to provide a device for cutting strips from pliable floor materials to make way for inlay strips wherewith to form decorative and useful borders and color combinations.

Another object of my invention is to provide a device for the purposes above set forth which may adjustably and accurately accomplish those purposes with a minimum of effort and with a minimum requirement for skill and experience in the operator thereof.

In the drawings:

Figure 1 is a isometric view of the lower side and one end of my device.

Figure 2 is a section on line 2—2 of Figure 1.

Figure 3 is a section on line 3—3 of Figure 2.

Figure 4 is an isometric view of my device in operation upon a linoleum floor.

Figure 5 shows my device mounted for cutting a circular channel, using my centering head.

Like parts are identified by the same reference characters throughout the several views.

My cutting device as described and shown herein is made for the purpose of cutting channels, grooves or strips in and from linoleum flooring or flooring of similar consistency but it will be obvious after an examination that my device may be used as well for any cutting process where cuts or kerfs of predetermined depth or size are desired and where accuracy in the width of cut for the channel or groove is a paramount requirement.

It is of advantage where flooring has already been laid or where flooring must first be laid before decorative features therein may be applied to lay out upon such a floor any desired design of inlay decoration for

whatever purpose and to be able to accurately and easily cut channels for the reception of inlay material and have the work rapidly done. My cutting device is best adapted to this type of work and consists of the following parts which make up my preferred structure.

Fundamentally my device comprises a knife or knives 10 which are so mounted within a frame 11 as to be adjustable in a plurality of directions with accuracy and with ease. The frame 11 comprises a block 12 and end pieces 13 and 14 providing an interior space which is divided into two sections by a partition 15. Across one of these sections and mounted in the end pieces 13 and 14 is a shaft 16 having portions 17 and 18 which are oppositely threaded and portions 19 outside the end pieces 13 and 14 which are squared to receive a wrench for purposes of adjustment.

Mounted upon threaded portion 17 of the shaft is a knife block 20 which comprises a holder for the knife 10 best shown in Figure 2 where it will be seen that this knife comprises a unitary screw threaded portion and a sharpened edged tool portion receivable in a threaded aperture 22 in the block 20. A set screw 23 mounted in an aperture 24 in the side of the knife block 20 provides means whereby the unitary knife element 10 may be "set" and prevented from turning in the knife block.

Upon portion 18 of the threaded shaft 16 another knife block 25 is mounted and comprises a counterpart of the knife block 20 except that its threaded mounting upon the portion 18 of the shaft 16 necessitates a threaded aperture at 26 adapted to receive the reversely contoured threads of the portion 18. This knife block is likewise provided with a set screw at 27 for the purpose of securing the knife 10 against rotation.

It will be seen from an examination particularly of Figures 1 and 3 that the knife blocks are securely held against rotation with the shaft 16 by reason of their position between the frame 11 and the partition 15 since these blocks have a sliding fit to permit their traverse from the middle of the shaft 16 out

wardly to the respective ends 13 and 14 of the frame.

Extending through either end of the frame and into the end pieces 13 and 14 I have provided set screws 28 and 29 which, when turned within their threaded mountings set against the journaled portions of the shaft 16 to prevent rotation thereof.

At a point in the bottom of the sides of the frame 11 midway between the end pieces 13 and 14 I provide channels 30 and 31 which are accurately machined to receive a guide bar 32, the purpose of which will be herein-after described. Likewise, at 33 and 34 in the end pieces 13 and 14, respectively, I have provided apertures through which the same guide bar 32 may be received where circular cutting is to be accomplished as hereinafter to be described and I have provided set screws 35 and 36 to secure the guide bar in apertures 33 and 34 so as to accurately secure the guide bar in said apertures for circular cutting. At 37 I have provided an aperture for convenience in handling my cutting device since it is preferable that the frame of my device be made heavy and therefore somewhat unwieldy and a hand hold most conveniently positioned in the frame is shown at 37.

As stated above my cutting device is of particular importance and of great usefulness in the cutting of channels in linoleum that has already been laid upon a floor and I have shown my device in Figures 2 to 5, inclusive, in various positions of adjustment and in various uses in such an operation. As shown in Figure 2 my device is placed upon a linoleum surfacing 40 which is laid upon an ordinary concrete or wood floor 41 and my guide bar 32 has been positioned midway of a strip 42 that is to be cut from the general body of linoleum.

Since the linoleum is resting upon material which is apt to dull the knives of my cutting device I have rotated the knives 10 in their respective knife blocks 22 and 25 only sufficiently to project the knife edges into the linoleum a substantial distance but not sufficient to cut clear through the flooring 41 and I have positioned the knife blocks 22 and 25 upon portions 17 and 18 of the threaded shaft 16 so as to cut a width of channel desired in the formation of the inlay. As shown in Figure 4 the guide bar 32 is secured to the linoleum surfacing and if necessary secured to the flooring 41 beneath said surfacing by hardened steel pegs 43 so that the frame 11 of my cutting device together with its accurately spaced knives 10 is guided along the guide bar 32 according to any desired pattern as laid out by the guide bar.

If a circular pattern is to be formed I set up my cutting device as indicated in Figure 5 with the guide bar 32 inserted through apertures 33 and 34, secured at a proper radius upon a peg 44, and the knives have been set

a proper distance from each other by rotation of the shaft 16 so as to cut a strip 45 of the desired width.

As a practical matter I have found in the use of my device that in setting the knives and knife blocks upon the shaft 16 it is preferable to place the proposed inlay strip between the knives 10 and to rotate the shaft 16 so as to bring the knives snugly against the sides of such proposed inlay strip; then upon removal of the inlay strip an additional slight turn of the shaft may be made before the set screws 28 and 29 are turned down upon said shaft thereby providing for a channel slightly less wide than the proposed inlay strip. By this means I have found that a smooth fit for the inlay strip is positively secured and that by reason of the accuracy of the cut made by my device the inlay strip will be received uniformly throughout the design cut in the floor in a satisfactory manner. Obviously after the cutting operation has been completed a slight tearing of the linoleum at the bottom of the cut is necessary but I have found that this is only sufficient to form a rough edge which will receive glue in a most satisfactory manner in gluing in an inlay strip as a final operation.

In order to provide for the cutting of an inlay groove which is narrower than a straight edge which may be laid in the groove 30, I provide an additional off set groove 30' in which the straight edge may be lodged so as to provide for guiding of my device at a time when the knives must necessarily be set closer together than would be permissible if the straight edge were lodged in the channel 30.

In Figure 5 I have shown a centering head through which in aperture 38 a guide strip 32 may be inserted and locked by means of set screw 38. The centering head may then be placed at the proper point in a linoleum floor and a workman may stand upon the centering head to locate it positively in that position while my device is being rotated about that center so as to cut a circular groove for an inlay.

It will likewise be apparent from the above description that my device may be used not only for cutting a channel from a laid floor so that an inlay strip may be inserted but the same device with the knives set at the position may be used to cut material from a stock piece of linoleum so that this cut strip will accurately fit the groove or channel which has been cut in the laid floor, thus obviating the necessity for accurate measurement of a channel that has already been cut or obviating the necessity for being extremely accurate in the cutting of the channel as is the case where an inlaid strip is already provided and the groove must be cut accurately to make the strip fit.

I claim:

1. A cutting device including a guide, a frame fitted to the guide, a screw having its end portions threaded oppositely, a knife block threaded upon either end of the screw and a knife for each block adjustably mounted for movement at an angle to the axis of the screw.
2. An inlay cutter comprising a frame provided with ways, a screw across the frame, a knife block threaded upon the screw for adjustment with reference to the frame a knife supported by the knife block and a guide bar for reception within the ways whereby to guide the frame and knife.
3. A cutting device comprising a frame including end pieces and a partition, a threaded shaft receivable in the end pieces across the frame, portions of said shaft being oppositely threaded, knife blocks threaded upon said portions of the shaft and engaging said partition, whereby they are prevented from rotation with the shaft and a knife adjustably receivable within each block.
4. A cutting device comprising a channeled frame including end pieces and a partition, of knife blocks within the frame and provided with knives, connections between the frame and the blocks for adjustment of the blocks within the frame, and a guide bar for reception in the channels of the frame.
5. A cutting device including an apertured frame, knives adjustable in the frame in a plurality of directions, and a guide bar receivable in one of said frame apertures to guide the frame on a circular path and receivable in another of said apertures to guide the frame along a path parallel with the axis of the guide bar.
